UNITED STATES PATENT OFFICE.

WILLIAM G. HOPKINS, OF PROVIDENCE, RHODE ISLAND.

BUTTON OR STUD.

SPECIFICATION forming part of Letters Patent No. 359,677, dated March 22, 1887.

Application filed January 8, 1887. Serial No. 223,755. (No model.)

To all whom it may concern:

Be it known that I, WILLIAM G. HOPKINS, of the city and county of Providence, and State of Rhode Island, have invented a new and useful Improvement in Buttons or Studs; and I do hereby declare the following specification, taken in connection with the accompanying drawings, forming a part of the same, to be a description thereof.

10 This invention relates to a button or stud having a shoe composed of two arms or parts, which are pivoted to the post and are arranged to be brought into a position parallel with the head of the article to hold the same in place, and are also capable of being turned into a position at right angles to the head, that the button or stud may be conveniently applied and removed.

15 The improvement consists in certain features of construction and arrangement, herein-after described and claimed.

In the accompanying drawings, Figures 1 and 2 represent side views of the button at right angles to each other, with the shoe parts 20 in their two positions. Fig. 3 represents a rear view of the button. Figs. 4 and 5 show vertical sections on lines $x x$ and $y y$, respectively. Fig. 6 shows a top view of the button with the front removed. Fig. 7 represents 25 the same view with the spring and its cover removed. Fig. 8 shows the post, the pin, the shoe-arms, and the spring detached and in perspective.

30 A is the button-head, which may be of any desired form or style. B is the post, which is made hollow, and is provided at its free end with ears $b b'$, to and between which the two shoe-arms C C' are pivoted side by side by a pin, D, passing through said ears and 35 through blocks $c c'$, secured to or integral with the arms C C', respectively. The post is secured to the back plate, A', of the button-head in any desired manner, but is preferably inserted in a hole, a' , in the plate, (which hole 40 is of a size to fit the post end,) and is soldered to the plate, thereby making its attachment more secure. Located in the hollow post and extending longitudinally of the same is a pin, E, which bears against the blocks $c c'$ at one 45 end and against a spring, f, at the other. This spring is located and concealed in the

5 head, and is preferably made by cutting and bending the portion f of a disk or plate, F, into the form of a tongue, as shown in Figs. 5 and 8. The spring-plate F is located within a cup-shaped piece, G, which is soldered to the 10 back plate, A', thereby keeping the plate F in proper position and relation to the pin E at all times for the spring-tongue f to act upon the pin. The blocks $c c'$ have two flat sides, 15 2 and 3, each, which, being engaged by the pin E, under pressure of the spring f , serve to lock the arms C C' in their two positions.

To apply the button, the arms or shoe parts C C' are turned into the position shown in Fig. 2, where they are held by the engagement of the pin E with the flat sides 2 2 of the blocks $c c'$. The arms are now easily passed through the button-holes, and are then turned into the position shown in Fig. 1, when the 20 pin E will engage the flat sides 3 3 on the blocks $c c'$ and lock the arms C C' in said position.

To remove the button, the arms are turned from the position shown in Fig. 1 to that in Fig. 2, when the button may be readily detached.

What I claim, and desire to secure by Letters Patent, is—

1. In a button or stud, the combination, 30 with the head, of a hollow post, B, secured thereto, the shoe-arms C C', pivoted side by side to the free end of said post and having flat faces 2 3 at right angles to each other, the pin E, located in the hollow post and engaging the shoe-arms, as described, and a spring 35 located and concealed in the head and bearing upon said pin, substantially as set forth.

2. The combination, with the head, of a hollow post, B, secured thereto and having 40 ears $b b'$, the shoe-arms C C', pivoted side by side to said ears and having blocks $c c'$, provided with flat faces 2 3, the pin E, located in said post and engaging the blocks $c c'$, a plate, F, having a spring-tongue, f, bearing upon 45 the pin, and a cover, G, secured to the head and holding the plate F in place, substantially as set forth.

WILLIAM G. HOPKINS.
